UNITED STATES PATENT OFFICE.

WILLIAM J. MCCESNEY, JR., OF ALBANY, NEW YORK, ASSIGNOR TO ALBANY PERFORATED WRAPPING PAPER CO., OF ALBANY, NEW YORK, A CORPORATION OF NEW YORK.

DESIGN FOR A TOY HOUSE BLANK.

Application filed June 17, 1925. Serial No. 13,806. Term of patent 3½ years.

To all whom it may concern:

Be it known that I, WILLIAM J. MCCESNEY, JR., a citizen of the United States of America, residing at Albany, county of Albany, and State of New York, have invented a new, original, and ornamental Design for a Toy House Blank, of which the following is a specification, reference being had to the accompanying drawing, forming part thereof.

The figure shows the design of the four sides of the house, in "knocked-down" condition.

I claim:—

The ornamental design for a toy house blank, as shown.

WILLIAM J. MCCESNEY, JR.
